UNITED STATES PATENT OFFICE.

THOMAS A. FITZGERALD, OF JACKSON, MICHIGAN.

GAS LOCK FOR MOTOR VEHICLES.

Application filed January 23, 1922. Serial No. 531,153.

To all whom it may concern:

Be it known that I, THOMAS A. FITZGERALD, a citizen of the United States of America, residing at Jackson, in the county 5 of Jackson and State of Michigan, have invented certain new and useful Improvements in Gas Locks for Motor Vehicles, of which the following is a specification, reference being had therein to the accompanying 10 drawings.

The invention relates to gas locks for motor vehicles and consists in the novel construction as hereinafter set forth.

In the drawings:

15 Figure 1 is a vertical longitudinal section through the lock;

Figure 2 is a horizontal section on line 2-2 of Figure 1;

Figure 3 is a plan view.

20 A is a casing which is connected at its opposite ends with the conduit B leading from the fuel supply tank and the conduit C extending to the carburetor. The casing A is formed with a series of valve seats D 25 therein for engaging rotary conical plug valves E, said valves having stems F which pass upward through packing glands G, and having springs H which yieldably hold them to their seats. I are angularly arranged 30 intersecting passages which extend in a zig-zag course between the several valve seats D, said passages being preferably formed by drilling from the outer side of the casing A and then plugging the outer 35 ends. The passages I together with the conduits B and C and the ports J through the valves E will, when properly arranged, form a continuous passage for the liquid fuel from the tank to the carburetor. This passage is 40 not, however, a straight one, but zig-zags back and forth through the casing A, so that it will be impossible to look through the casing from one end to the other.

The valve stems F pass upward into a 45 casing K which has a glass or transparent cover L and visible through this cover are indicators M. The valve stems are further provided with handles N between the casing K and the casing A so that any one of said 50 stems can be rotatively adjusted by means of the handle.

With the construction as described, the fuel passage may be blocked by the turning of one or more of the valves E so as to dis-

connect from the angling passages. In this 55 position it is impossible for any one to determine what adjustment is required to bring the valve again into registration, for the valve itself is concealed. However, the indicators M are numbered and anyone familiar with the combination can readily 60 set the valves so as to form a continuous unobstructed passage. Nevertheless, it would be impossible for one not knowing the combination to so set the valves, for all must 65 be properly adjusted before the fluid is permitted to flow and experimenting on one will be of no avail if another valve is out of registration. Thus, the locking is effectual, but at any time a person knowing 70 the combination can quickly adjust the valves to open position.

What I claim as my invention is:

1. A gas lock comprising a casing formed from a solid piece of metal and having a 75 passage therethrough, a series of valves in said casing for obstructing said passage, each valve being ported to open communication with said passage when properly set, indicators secured to said valves, 80 a casing inclosing said indicators and having a transparent wall therein for viewing said indicators and an index cooperating with said indicators to facilitate the setting of said valves in proper registration. 85

2. A gas lock comprising a casing formed from a solid piece of metal and having a bored out zig-zag passage therethrough with a series of valve seats at intermediate points in said passage, a series of rotary plug 90 valves engaging said seats and adapted to open communication through said zig-zag passages, stems for operating said valves, indicators at the upper ends of said stems, a casing having a transparent top for enclosing said indicators and permitting the viewing of the same, and handles for operating said valves engaging said stems intermediate said casing for the indicators and the casing for the valves. 95

3. A gas lock comprising a casing formed from a solid piece of metal and having a series of conical valve seats therein and bored out zig-zag passages connecting said seats, a series of conical plug valves respectively engaging said seats and ported for registration with said zig-zag passages, stems for operating said valves, indicators 105

mounted on said stems, a casing for enclosing said indicators provided with a transparent top, and handles engaging said stems intermediate said indicator casing and said 5 valve casing, for the purpose described.

4. A gas lock comprising a casing formed from a solid piece of metal having a zig-zag passage therethrough and a detachable cover therefor provided with shouldered 10 portions, said passage being formed by a plurality of intersecting bored out passages plugged at their outer ends, a series of conical plug valves in said casing for obstructing said zig-zag passage, each valve being ported 15 to open communication with said passages when properly set, a tensioning element bearing against the shouldered portions of said detachable cover and said valves respectively, means for moving said valves

and means for indicating their open positions.

5. A gas lock comprising a casing formed from a solid piece of metal and having a zig-zag passage therethrough, said passage being formed by a plurality of intersecting bored out passages, a cover detachably secured to said casing and provided with apertures therein, a series of plug valves in said casing for obstructing said zig-zag passage, each valve being ported to open communication with said passage when properly set, springs in said apertures and bearing against said plug valves to hold the same properly positioned, means for moving said valves, and means for indicating their open position.

In testimony whereof I affix my signature.
THOMAS A. FITZGERALD.
